CLAIM

The ornamental design for a combined solar powered electronic display assembly with charging station, as shown and described.

DESCRIPTION

FIG. 1 is a front perspective view of a combined solar powered electronic display assembly with charging station; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; and, FIG. 8 is a rear perspective view thereof.

The broken lines shown represent the portions of the combined solar powered electronic display assembly with charging station that form no part of the claimed design.

1 Claim, 8 Drawing Sheets
